(57) **CLAIM**

The ornamental design for a t-shirt with screen display, as shown and described.

DESCRIPTION

FIG. 1 shows a t-shirt with screen display, showing my new design;

FIG. 2 show a front view thereof;

FIG. 3 show a side view thereof; and,

FIG. 4 show a top view thereof.

1 Claim, 2 Drawing Sheets# US D791,443 S
